VIBRATING BODY (SENSOR) FOR MEASURING
THE CONCENTRATION OF SOLID PARTICLES
IN A SUSPENSION

Berth Ulrik Gustafsson, Osterskar, Sweden, assignor to
Projectus Industriprodukter AB, Stockholm, Sweden

Filed Mar. 29, 1972, Ser. No. 239,415

Term of patent 14 years

Int. Cl. D24—99; D10—99

U.S. Cl. D16—2 C

FIG. 1

FIG 2

FIG. 3

FIG. 1 is a perspective view of a vibrating body (sensor) for measuring the concentration of solid particles in a suspension, embodying my new design;

FIG. 2 is a perspective view of the vibrating body as seen from the rear of FIG. 1; and

FIG. 3 is a side elevation thereof.

I claim:

The ornamental design of a vibrating body (sensor) for measuring the concentration of solid particles in a suspension, as shown and described.
